DISPLAY SIGN

John Hays Hammond, Jr., Gloucester, Mass.

Application December 18, 1937, Serial No. 180,501

13 Claims. (Cl. 40—130)

This invention relates to display signs and more particularly to a sign composed of a plurality of rapidly moving lights.

The invention further relates to a display system in which the lights move so rapidly that they complete a full cycle in less than one sixteenth of a second so that the paths traversed by the lights appear as continuous luminous lines.

The invention also relates to automatic means for changing the characters of the sign so that various words or symbols may appear successively on the sign.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description, taken in connection with the accompanying drawings forming a part thereof, in which

Fig. 1 is a front elevation, partly broken away, of a display system constructed in accordance with this invention;

Fig. 2 is an enlarged detail view of part of the mechanism shown in Fig. 1;

Fig. 3 is a side elevation of the mechanism shown in Fig. 2, together with the control apparatus;

Fig. 4 is a sectional plan view taken on line 4—4 of Fig. 2, and

Fig. 5 is a diagrammatic view of the path followed by one of the lights in forming a character.

Like reference characters denote like parts in the several figures of the drawings.

In the following description and in the claims parts will be identified by specific names for convenience, but they are intended to be as generic in their application to similar parts as the art will permit.

Referring to the drawings and more particularly to Fig. 1, a display sign 10 is shown as provided with a plurality of pantographs 11 which are pivoted at 12 to a cross bar 13. At the top of each pantograph may be mounted one or more lamps 15. The lower ends of each pantograph 11 extend into a casing 16 and are provided with a pin 17 which engages two slots 18 and 19 provided in two T-shaped members 20 and 21 respectively. Each pantograph is provided with a separate control apparatus, one only of which is described below and shown in detail

in the drawings. It is to be understood that this control apparatus is duplicated for each of the pantographs employed.

The members 20 and 21 are slidably mounted for vertical and horizontal motion respectively in a frame 22, which is secured to the top of the casing 16, and are provided at their ends with pins 25 and 26. These pins engage slots provided in the ends of two arms 27 and 28 which are pivoted on a bar 29 secured to the casing 16. Two compression springs 30 and 31 are mounted between the arms 27 and 28 and the frame 22.

Pivoted to the arms 27 and 28 are two rollers 32 and 33 which engage two cams 35 and 36. These cams are secured to two sleeves 37 and 38 which slide on two shafts 39 and 40 respectively but are mounted to rotate therewith. The shafts 39 and 40 are secured to the casing 16, in any convenient manner.

Rigidly secured to the sleeves 37 and 38 are a plurality of other cams 41, 42, etc. and 45, 46, etc. respectively. The sleeves 37 and 38 are provided with grooves which are adapted to receive two yokes 47 and 48 formed on the ends of an L-shaped member 49 which is journaled to slide axially with a shaft 50. The shaft 50 is mounted for sliding and rotational movement in the frame 16. Secured to the shaft 50 is a commutator 51 made of insulating material and provided with a plurality of conducting segments 52 (Fig. 3) which correspond in position to the cams 36, 45, 46, etc. Surrounding the shaft 50 and tending to move the commutator 51 and member 49 to the left, as viewed in Fig. 3, is a compression spring 53.

Secured to the end of the shaft 50 is a piston 54 which is adapted to reciprocate in a cylinder 55 mounted on the casing 16. The cylinder 55 is provided with a vent 56. Slidably but not rotatably mounted on the shaft 50 is a gear 57 which meshes with two other gears 58 which are secured to the shafts 39 and 40 respectively. Meshing with the gear 57 is a pinion 59 which is secured to the shaft of a motor 60. This motor is driven from any suitable source of power such as an A. C. supply 61.

Secured to the casing 16 is a cylinder 62 (Fig. 2) in which reciprocates a piston 63 which is attached to a piston rod 65. Surrounding this rod and tending to hold the piston 63 at the lower end of the cylinder 62 is a compression spring 67. The cylinder 62 is provided with a vent 68 at its upper end.

Mounted on a bracket 69 which is secured to the casing 16 is a second cylinder 70 which is

similar in construction to cylinder 62 and which is provided with a piston rod 71. Secured to the rod 71 is an arm 72 of insulating material to which is attached a segment 73 of conducting material. The lamp 15, which is mounted at the top of one of the pantographs 11, is connected to a source of power 75 thru two sets of contacts 76-77 and 78-79. The contacts 76 and 77 are normally engaged by the conducting segment 73 and the contacts 78 and 79 engage the commutator 51.

Slidably mounted in the casing 16 and in a bracket 80 are a plurality of rectangular shaped bars 81, 82 and 83 (Figs. 2 to 4) which are provided with a plurality of notches 85 of varying widths. Located above the bars 81-83 and pivotally mounted on a rod 86 are a plurality of bars 87 to 93. Between these bars are spacers 95. The L shaped member 49 is provided with a lug 96 which engages any of the bars 87 to 93 when they are in an operative position as shown in Fig. 2.

Located beneath the bars 87-93 is a cylinder 97 (Figs. 2 and 3) in which reciprocates a piston 98 to which is attached a T shaped piston rod 99 for engaging the bars 87-93. Surrounding the piston rod 99 and tending to hold the piston 98 at the bottom of the cylinder 97 is a compression spring 100. The cylinder 97 is provided with a vent 101.

30 Mounted on a bracket 102 are three cylinders 103, 104 and 105 (Figs. 3 and 4) in each of which reciprocates a piston 106. Connected to the pistons 106 are three piston rods 107 the other ends of which are attached to the bars 81, 82 and 83. 35 Surrounding the piston rods 107 are three compression springs 108 which tend to move the bars 81, 82 and 83 downward as viewed in Fig. 4. The three cylinders 103, 104 and 105 are provided with vents 109.

40 For controlling the operation of the display device a control mechanism is provided which comprises a perforated roll 111 of paper or other suitable material which is drawn over a tracker bar 112 at a uniform or variable rate of speed 45 by any well known form of mechanism for such purpose (not shown). The tracker bar 112 is provided with a plurality of groups 115 to 121 of three holes each and with three individual holes, 122, 123 and 124. These holes are connected by 50 tubes 125 to a pneumatic relay mechanism 126. This mechanism is provided with outlet tubes which are arranged in a plurality of groups 128 to 134 of three tubes each and three individual tubes 135, 136 and 137. The relay mechanism is 55 so constructed that when a perforation in the roll 111 passes in front of a hole in the tracker bar 112 air under pressure will be caused to enter the corresponding outlet tube.

The three outlet tubes of each group 128 to 134 60 are connected to the three cylinders 103, 104 and 105 of each of the mechanisms controlling the various pantographs 11. The tube 135 is connected to the cylinder 55 and by a branch tube 140 to all the other corresponding cylinders 55 65 of the control apparatus for the other pantographs. The tube 136 is connected to the cylinder 62 and by a branch tube 142 to the cylinder 70. The tube 137 is also connected by a branch tube 143 to all the other corresponding cylinders 62 70 and 70. The tube 137 is connected to the cylinder 97 and by a branch tube 144 to all the other corresponding cylinders 97.

The roll 111 is provided with three individual perforations 145, 146 and 147 and a plurality of 75 groups 148 to 154 of perforations which vary in

number and position. The groups, however, corresponding to the groups of holes 115 to 121 in the tracker bar 112.

In the operation of the display device the roll 111 is moved over the tracker bar 112, preferably at a uniform rate, by any suitable mechanism provided for the purpose. The perforation 146 will first uncover the hole 123 causing air under pressure to be supplied, by the tube 136, to all the cylinders 62 and 70. This will cause the piston rods 65 and 71 of these cylinders to be moved outwardly and into engagement with the arms 27 and 28 which will be moved upwardly and to the left respectively, thus lifting the rollers 32 and 33 away from their corresponding cams. At the same time the contact segment 73 will be moved to the left, thus breaking the circuit to the lamp 15, the light from which is thereby extinguished.

The perforations 145 and 147 next uncover the holes 122 and 124, admitting air under pressure to all the cylinders 55 and 97. When air enters the cylinder 55 the piston will be moved to the extreme right as shown in Fig. 3. This by means of the rod 50 will move the L shaped member 49, together with the commutator 51 and all of the cams, to the extreme right hand position. At the same time the air entering the cylinder 97 causes the rod 99 to be moved upward, thus rotating all of the bars 87 to 93 to a horizontal 30 position.

The groups of perforations 148 to 154 will next uncover the corresponding holes in the tracker bar 112. The group 151 for example consists of only one perforation in the left hand position 35 which will cause air under pressure to be supplied to the cylinder 103. This moves the bar 81 upward into the position shown in Fig. 4. The group 152, which is shown as consisting of one perforation in the center position, will cause the 40 bar 82 of the corresponding mechanism to be moved upward. The group 153, comprising two perforations in left and center positions, will cause both the bars 81 and 82 of the corresponding mechanism to be moved upward. In a similar manner the various groups of perforations will cause various movements of the bars 81 to 83 in the corresponding mechanisms depending on the number and positions of the perforations.

When the bar 81 is moved upward, as shown in 50 Fig. 4, it will cause three of the notches 85 in the three bars 81, 82 and 83 to be in line with the bar 87. When only the bar 82 is moved upward it will cause three of the notches 85 in the three bars 81, 82 and 83 to be in line with the bar 88. 55 In a similar manner by moving any one or combination of the bars 81, 82 and 83 it is possible to cause the notches 85 to line up under any desired one of the bars 87 to 93.

As the roll 111 continues to move over the 60 tracker bar 112 the perforation 147 will cease to uncover the hole 124 which will shut off the supply of air to the tube 137 and will connect it to the exhaust thus allowing all the pistons 98 in the cylinders 97 to move downward under the 65 action of the springs 100. This causes the rod 99 to move out of engagement with the bars 87-93 leaving them free to rotate in a counter-clockwise direction under the action of gravity.

The bar 87 will drop into the three notches 85 70 which are in line under this bar as shown in Fig. 4. The other bars 88-93 will not drop down, however, as at no other place are three notches 85 in line. In each of the other similar mechanisms associated with the other pantographs one of the 75

bars 87—93 will drop down depending upon how the bars 81 to 83 have been moved under the action of the groups of perforations 148—154 as already described.

5 As the roll 111 continues to move upward the perforation 145 will cease to uncover the hole 122 thus causing the tube 135 to be connected to the exhaust. This will allow the piston 54, rod 50 and member 49, together with the commutator 51 and all the cams, to move to the left under the action of the spring 53 as viewed in Fig. 3. This motion will continue until the lug 96 engages the bar 87 the right hand end of which has been moved up into the path of the lug 96 as shown in Fig. 2. The commutators and cams of the other mechanisms will be moved in a similar manner until the lugs 96 engage the particular bar 87—93 which has been moved into operative positions as already described.

10 20 As the roll 111 continues to move upward the perforation 146 will cease to uncover the hole 123 thus causing the tube 136 to be connected to the exhaust which will allow the rods 65 and 71 to be returned to their initial positions thus allowing the arms 27 and 28 to be moved downward and to the right under the actions of the springs 30 and 31 respectively. This allows the rollers 32 and 33 to engage the cams 35 and 36 which have been thus set in position and which are continually rotated at a relatively high speed by the motor 60 acting thru the gears 59, 57 and 58. The speed is preferably selected within the limits of the persistency of vision such as above sixteen cycles per second so that the letter appears as a stationary and complete character.

35 The rollers 32 and 33 of the other mechanisms will also drop upon various cams depending upon the position assumed by the member 49, which, as already described, is determined by which one of the bars 87—93 is in an operative position. Thus for example the rollers 32 and 33 of the mechanism controlled by the group of perforations 152 will engage the cams 41 and 45 respectively.

40 45 As the cams 35 and 36 rotate under the rollers 32 and 33, the arms 27 and 28 and therefore the members 20 and 21 will move in a manner determined by the shape of these cams. The motions of the members 20 and 21 will be combined and transmitted by means of the pin 17 to the pantograph 11 which will cause the lamp 15 to move in a manner determined by the shape of the cams 35 and 36. In this case the cams are shaped so as to cause the lamp 15 to follow the curved path 157 of Fig. 5.

50 55 The commutator 51 is rotated by means of the gear 57 at the same speed as the cams and the segments 52 which are in line with the contacts 78 and 79 are so designed that the lamp 15 will be lit while it is travelling the full line sections of the curved path 157 and will be extinguished while it is travelling the dotted line sections of this path. As the lamp 15 traverses the complete curved path 157 in less than one-sixteenth of a second the visual effect produced by its motion will be the letter A as shown in the full lines of Fig. 5.

60 65 The second set of cams 41 and 45 and the second set of segments 52 on the commutator 51 may be so designed that the lamp 15 will be caused to follow a curved path which will produce some other letter, such as the letter B. The third set of cams 42 and 46 and third set of segments 52 will produce a third letter, such as the letter C, and so on. In this way any desired number of

75 letters, digits and characters of any description may be produced by constructing the proper cams and commutators. The cams and commutators are, of course, selected in accordance with the combination of characters required in a particular sign.

80 The characters formed by the lamps 15 shown in Fig. 1 are determined by the number and location of the perforations in the groups 148 to 154. These characters continue to be formed by the lamps 15 as long as no more perforations appear on the roll 111. When, however, it is desired to change these characters a new set of perforations are provided in the roll 111. The perforations 145, 146 and 147 remain similar to those shown 15 in Fig. 3 and operate the mechanisms in an identical manner to that already described. The groups of perforations 148 to 154 may be changed as to number and arrangement so as to produce a new set of characters.

20 In this way it is possible to provide a roll 111 which will cause any desired number of words to be produced consecutively by the display device.

25 While only a single lamp is shown on each pantograph it is to be understood that any desired number of lamps may be used either white or colored so that it would be possible to produce the words in colored lights as well as in white.

30 Only a limited number of lights, selector rods, cams and commutators have been shown for purposes of illustration but it is understood that any desired number may be provided in order to produce words of any length and type of character.

35 The device may be adapted to electrical operation by substituting contact means and electrical relays for the pneumatic control apparatus which has been shown merely for purposes of illustration. If a single symbol only is to be shown for a long period of time the pneumatic control means may be omitted and the cams may be set 40 manually as required. In that event the cams may be made replaceable and shifting of the shaft 50 axially could be dispensed with.

45 Although only a few of the various forms in which this invention may be embodied have been shown herein, it is to be understood that the invention is not limited to any specific construction but might be embodied in various forms without departing from the spirit of the invention or the scope of the appended claims.

50 What is claimed is:

1. A display sign comprising a plurality of light sources, means repeatedly and simultaneously moving each of said light sources in predetermined paths to trace independently designated 55 characters by each source, and means rendering said light sources luminous over a portion of that path corresponding to said characters.

2. The invention set forth in claim 1 in which the light sources are moved at a speed above the 60 persistency of vision so that permanent stationary characters appear to the eye to be formed thereby.

3. A display sign comprising a point light source, means comprising a set of cams for repeatedly moving said light sources in predetermined paths to trace designated characters, means rendering said light sources luminous over a portion of that path corresponding to said designated characters and means rendering various 65 cams of said set operative in accordance with the selected character.

4. A display sign, comprising a light source, cam operated means adapted to cause said light source to travel in a recurrent predetermined 70 75

path adapted to form a designated character, additional cam means associated with said first cam means and adapted to cause said light source to form other characters, and means selectively rendering said cam means operative in accordance with the character desired.

5. The invention set forth in claim 4 in which the various cam means are mounted on the same shaft and means is provided for shifting said shaft axially for bringing said cam means into 10 operative position.

6. The invention set forth in claim 4 in which a commutator is provided having segments corresponding to each of said cam means and adapted 15 to cooperate therewith to render said light source luminous over a predetermined portion of the path of travel thereof selected to form the desired character.

7. A display sign, comprising a light source, a 20 pantograph controlling the position of said light source, means actuating said pantograph to cause said light source to repeatedly follow a predetermined path, said means comprising linkages operatively connected to said pantograph and rotating cam means engaging said linkages, said cam means comprising a shaft carrying a plurality of different cams, means shifting said shaft axially to bring selected cams into operative position with respect to said linkage, a commutator 25 carried by said shaft, said commutator having segments corresponding to each of said cam means and adapted to render said light source luminous over a portion of each path corresponding to the designated character, said commutator being shiftable with said shaft to bring the different 30 segments into operative position.

8. The invention set forth in claim 7 in which a pair of cam means and commutators are provided to control the movement of said pantograph in coordinate directions.

40 9. The invention as set forth in claim 7 having a bracket to control the axial position of said

shaft, a plurality of stop members to limit the movement of said bracket and remote control means to actuate said stop members.

10. The invention as set forth in claim 7 having a plurality of stop members for limiting the 5 movement of said bracket, and means for actuating said stop members comprising a set of sliding bars having grooves therein adapted to register with the different stop members in accordance with the relative positions of the various bars, remote control means for actuating said bars, releasing said stop members and returning said bracket to a predetermined zero position prior to each setting operation.

11. The invention as set forth in claim 7 having a plurality of stop members for limiting the movement of said bracket, means for actuating said stop members comprising a set of sliding bars having grooves therein adapted to register with the different stop members in accordance 10 with the relative positions of the various bars, remote control means for actuating said bars, releasing said stop members returning said bracket to a predetermined zero position prior to each setting operation, said remote control means comprising a pneumatic selector adapted to operate with a perforated control sheet whereby the cam selection is automatically effected by movement of said perforated sheet.

12. The method of producing a display sign 20 which comprises simultaneously moving a plurality of light sources in selected recurrent paths and rendering each of said light sources luminous over a portion of the respective path corresponding to a designated character.

30 13. The method set forth in claim 12 in which the light sources are moved at a speed above the persistence of vision whereby a permanent stationary visual impression of the selected characters is obtained.

JOHN HAYS HAMMOND, JR.
